UNITED STATES PATENT OFFICE.

ORIN B. RAND, OF KALAMAZOO, MICHIGAN.

IMPROVEMENT IN DOOR-LATCHES.

Specification forming part of Letters Patent No. 140,307, dated June 24, 1873; application filed November 29, 1872.

To all whom it may concern:

Be it known that I, ORIN B. RAND, of Kalamazoo, in the county of Kalamazoo and State of Michigan, have invented an Improvement to my Double-Acting Spring-Bolt Door-Fastener, for which Letters Patent of the United States were issued February 2, A. D. 1869, and No. 86,448.

My improvement consists in attaching to the patented invention, above referred to, a device for locking the knob, so as to secure the bolts in fastening the door, or leaving it free to open as desired.

In the use of my invention it is often desirable to have the bolt at the bottom of the door extend further than the one at the top. I accomplish this in my improvement, by making the lever-flange B with one arm the longer, as shown at H in the accompanying drawing. This arm, connected to the bolt by the rod C, admits of its extending further down in the operation. When this long extension is not desired the rod C may be attached to the arm of the flange, equidistant from the center, as shown at H in the drawing, and then both bolts extend alike.

To get a more perfect operation in my invention I construct the spindle L similar to those commonly used for knob-latches, except that that portion of it extending through the door is made round and turns in the cylinder in operating, as shown in the drawing, Fig. 3, to which any knob in common use may be fitted in the ordinary way.

By my improvement I fasten the bolts, in operating them, by placing, at the opposite end of the spindle from the knob and fastened

to the wood inside, a metal plate, having a square opening in the center to admit that end of the spindle to fasten or secure the bolts, as shown at I and E. And to cause the spindle to operate the bolts in the way above indicated, I provide a wire spiral spring sufficiently strong between the flange and the wood of the door, toward the knob, as shown at S, in the drawing.

Figs. 1 and 2, in accompanying drawing, show the application of my invention as improved.

My invention, as improved, is operated by taking the knob G in one hand and pressing slightly on the door with the other, or with the foot at the bottom, and turning the knob one-quarter around, when the spring S forces the spindle into the opening I, in the plate, and secures the bolts as desired.

Fig. 2 represents the attachment of my invention as improved. Fig. 3 represents the form of the spindle L and the screw-cylinder P, as used in my improvement.

What I claim as an improvement to my invention, and desire to secure by Letters Patent, is—

The spindle L, spiral spring S, cylinder P, knob G, and plate I, all arranged so that the knob is locked from turning in combination with the lever-flange B, operating the rods and spring-latches, when constructed, arranged, and operated as described and shown, for the purpose set forth.

ORIN B. RAND.
